UNITED STATES PATENT OFFICE.

FERNAND JAVAL, OF PARIS, FRANCE.

DESIGN FOR A BOTTLE.

Application filed August 3, 1922. Serial No. 3,279. Term of patent 14 years.

To all whom it may concern:

Be it known that I, FERNAND JAVAL, a citizen of the Republic of France, residing at Paris, France, (whose post-office address is c/o Parfumerie Houbigant, 19 Rue du Faubourg Saint-Honore, Paris, France), have invented a new, original, and ornamental Design for a Bottle, of which the following is a specification, reference being had to the accompanying drawing, forming a part thereof.

In the drawing,
Fig. 1 shows a perspective view of the bottle.

Fig. 2 is a top view thereof.

I claim:—

The design for a bottle substantially as shown.

FERNAND JAVAL.
